(57) **CLAIM**

I claim the ornamental design for an engine-shaped barbecue, as shown and described.

DESCRIPTION

FIG. 1 is a perspective view of an engine-shaped barbecue showing my new design, with the cover in an open position; FIG. 2 is a perspective view thereof, with the cover in a closed position;

FIG. 3 is a front elevational view with the cover in a closed position;

FIG. 4 is a rear elevational view with the cover in a closed position;

FIG. 5 is a left-side elevational view with the cover in a closed position;

FIG. 6 is a right-side elevational view with the cover in a closed position;

FIG. 7 is a top plan view with the cover in a closed position; and,

FIG. 8 is a bottom plan view with the cover in a closed position.
